GLASSWARE SPRAYING APPARATUS

Albert S. Jackson, Wood River, Ill., and Ernest W. Summers, Richmond Heights, Mo., assignors to Owens-Illinois Glass Company, a corporation of Ohio

Application June 19, 1942, Serial No. 447,628

3 Claims. (Cl. 91—45)

Our invention relates to apparatus for spraying or coating glassware including bottles, jars and other articles, with a lubricating material such as water or other fluid containing a lubricant. The invention is useful for spraying such articles after they have passed through an annealing leir but before handling or removal from the annealing leir conveyor.

The clean dry surfaces of the glassware as it emerges from the annealing leir are particularly susceptible to surface injuries such as scratches or abrasions. Frictional contact of the articles with each other while being handled during inspection and packing is liable to produce scratching and marring of the contacting surfaces, which also greatly weakens the articles.

An object of the invention is to provide suitable apparatus for coating the articles with a lubricating material so that the susceptibility to such injuries is greatly reduced.

A further object of the invention is to provide an apparatus by which the coating material may be uniformly applied to the entire surface of the articles under treatment in an economical and efficient manner.

Other objects of the invention will appear hereinafter.

Referring to the accompanying drawings which illustrate an apparatus constructed in accordance with the principles of our invention:

Fig. 1 is an elevational view of the apparatus in operative relation to an annealing leir;

Fig. 2 is a cross-sectional elevation at the line 2—2 on Fig. 1;

Fig. 3 is a section at the line 3—3 on Fig. 2;

Fig. 4 is a part sectional plan view of the suction duct; and

Fig. 5 is a section through the booth at the line 5—5 on Fig. 2.

The annealing leir 10 which may be of conventional construction, includes a traveling endless belt or apron conveyor 11 of wire mesh construction which provides a foraminous support for the bottles B or other glass articles and by which said articles are conveyed through the leir. The spraying apparatus includes in general terms a booth 12 positioned over the leir conveyor and extending transversely thereof, a battery of spray guns 13 having nozzles 13a mounted over the booth for applying spray to the bottles, a suction fan 14 and duct 15 for causing a down draft of the spray through the booth, a tank or tanks 16 containing a supply of the spraying material, and a piping system together with valves, pressure reducing means, and pressure gauges.

The booth 12 which is positioned over the leir conveyor 11 and extends transversely thereof, includes end walls 17 (Fig. 2) mounted on channel irons 18 which may form part of the conveyor 10 supporting frame, and side walls 19 spaced above the apron 11 to leave an open passageway for the glassware. The spray guns 13 are mounted on a rod 20 carried on straps 21 which are bolted to the end walls of the booth. The nozzles are positioned directly over the booth and arranged to direct a spray downwardly through the booth into contact with the bottles. The jet of spray from each nozzle is flared or spread outwardly as indicated by broken lines 22 (Figs. 2 and 5), to cover 15 an area which is roughly indicated by the lines 23. This distribution of the spray is such that each bottle or article while passing beneath the booth is completely enveloped in the spray and given a substantially uniform coating of the lubricant 20 over its entire surface.

In order to maintain a downward draft through the booth and thereby effectively apply the spray to the bottles, a suction apparatus is provided, including the suction fan or pump 14 and the duct 25 15 leading therefrom. The duct includes a cylindrical section 25 extending from the fan 14 along the side of the leir, a section 26 extending beneath and transversely of the leir conveyor, directly beneath the booth 12, and an intermediate 30 tapered section 27.

The section 26 is provided with partition walls 28 extending lengthwise thereof and dividing it into a suction chamber 29 and channels 30. The chamber 29 is extended into the section 27 (Fig. 35 4) and is provided with a damper 31 for regulating the distribution or proportioning of the flow through the said chamber and the channels 30. The walls 28 are provided with ports 32 and 33 at intervals therealong. The walls 28 also terminate at a point spaced inwardly from the end wall 34 of the chamber. The openings thus provided at intervals along the suction chamber serve to regulate the distribution of the gases drawn through the conduit and facilitate the even distribution of the spray to the surfaces of the bottles throughout the length of the booth. The side walls of the booth serve to protect from outside drafts, direct the spray downwardly and aid in its proper and uniform distribution.

50 A damper 35 is provided in the duct for adjustably regulating and controlling the force of the downward draft through the booth. The damper is adjustable by means of a handle 36 and held in adjusted position by a ribbed holding 55 strip 37.

The spraying fluid is supplied from a tank or tanks 16. Two tanks are preferably employed so that one may be in use while the other is being filled thus providing for continuous operation. Air under pressure, for example, 60 lbs., is supplied through a pressure pipe 38 and distributed to the tanks through a branch pipe 39 for maintaining a continuous pressure upon the liquid in the tanks. The pressure pipe 38 also supplies air through a pressure reducing device 40 to a pipe 41 leading to a manifold or header 42 through which the air is distributed to the spray guns 13. Air under pressure for agitating the liquid in the tanks may be supplied through a pipe 43 and header 44, the ends of the latter extending upwardly through the bottoms of the tanks. The spraying fluid is conducted to the spray guns through a header 45, pipe 46, manifold 47 and pipes 48.

The spray booth as shown is located a short distance beyond the discharge end of the leer tunnel, permitting the bottles to cool to a suitable temperature before the spray is applied. The bottles are taken off the leer conveyor after the spraying operation for the usual inspection and packing.

Modifications may be resorted to within the spirit and scope of our invention.

We claim:

1. Apparatus for applying a lubricant to the surfaces of articles, said apparatus comprising a support for the articles, a booth positioned over the said support and having side walls spaced above the support for the passage of said articles, spray nozzles above said support in position to direct the lubricant downward through the booth and spray it on said articles, a suction chamber positioned beneath the support and booth, said chamber having side walls provided with port openings at intervals therealong, channels communicating with said openings, and means for applying suction to said chamber and said channels and thereby causing and distributing a substantially uniform distribution of the spraying material to the surfaces of the articles beneath the booth.

2. Apparatus for applying a lubricating fluid to the surfaces of articles, said apparatus comprising a horizontal support for the articles, a booth positioned over said support, spray nozzles above said support in position to direct the lubricating fluid downwardly through the booth and spray it on the articles on the support, a suction chamber positioned beneath the support and booth, said chamber having side walls provided with port openings at intervals therealong, channels communicating with said openings, means for applying suction to said chamber and said channels, thereby causing and distributing a down draft through the booth and effecting a substantially uniform distribution of the lubricating fluid to the surfaces of the said articles, and a valve interposed between said chamber and the suction means and adjustable to adjustably vary the draft through said port openings.
3. Apparatus for applying a lubricating fluid to the surfaces of articles, said apparatus comprising a horizontal support for the articles, a booth positioned over said support, a row of spray nozzles positioned above the support and arranged to direct the lubricating fluid downwardly through the booth and spray it onto a row of articles on said support, a suction chamber positioned beneath the support and booth and extending lengthwise of said row of nozzles, said chamber being open at one end and having side walls provided with port openings at intervals therealong, channels extending along said chamber at opposite sides thereof and open to said chamber through said port openings, a suction fan, a conduit extending from the fan to said channels and said open end of the chamber, said fan being operable to apply suction to said chamber and channels and thereby causing and distributing a down draft through the booth and distributing the spraying material to the surfaces of the said articles, and a valve in said open end of the chamber adjustable to regulate the distribution of the air flow through said chamber and channels.
